(57) **CLAIM**

The ornamental design for bottle holder, as shown and described.

DESCRIPTION

FIG. 1 is a front perspective view of a bottle holder of my present invention.

FIG. 2 is a rear perspective view of FIG. 1.

FIG. 3 is a front elevation view of FIG. 1.

FIG. 4 is a rear elevation view of FIG. 1.

FIG. 5 is a right side view of FIG. 1.

FIG. 6 is a left side view of FIG. 1.

FIG. 7 is a top plan view of FIG. 1.

FIG. 8 is a bottom plan view of FIG. 1; and,

FIG. 9 is an illustration view of the invention in an environmental use-condition along section 1, and to which no claim is made.

The dash-dash lines in FIGS. 1-9, indicate disclaimed portions to which no claim is made. The broken cut line (dash-jog-dash) in FIGS. 1-6 indicates a break-portion of a longer member, and to which no claim is made. The dash-dot-dash line in FIG. 9 is a section indicator demarking an illustration portion portion. No claim is made to portions that are not shown.
